UNITED STATES PATENT OFFICE.

WILLARD C. BEACH, OF NEWARK, NEW JERSEY.

COMPRESSED-AIR TANK HAVING INTERCHANGEABLE PAINT CONTAINERS.

Application filed October 21, 1922. Serial No. 595,915.

To all whom it may concern:

Be it known that I, WILLARD C. BEACH, a citizen of the United States, residing in Newark, county of Essex, and State of New Jersey, have invented new and useful Improvements in Compressed-Air Tanks Having Interchangeable Paint Containers, of which the following is a specification.

The main purpose of this invention is to provide a tank, as used in combination with devices for spraying paint under air pressure, with a plurality of containers for paint or the like of different colors or kinds, whereby one container may be exchanged for another in a rapid and easy manner.

Another object is to so arrange the paint containers as to avoid having the paint come in contact with the walls of the tank, which act merely as a receptacle for the compressed air and are thus at all times wholly free of the paint.

A further object is in the provision of paint containing cans provided with handles accessible from their interiors and having individual covers, the cans being spaced from the wall of the tank and below its upper edge.

These objects are accomplished by the novel construction and arrangement of parts herein described, hereafter claimed, and shown in the annexed drawing, in which:—

Figure 1 is a plan view of the preferred embodiment of tank and container, parts being broken away to show the construction.

Figure 2 is a partial side elevational, partial sectional view of the same.

As shown in the drawing the tank 10 is plainly cylindrical, its tubular wall being cut squarely across at its ends in the lower 40 of which is secured a flanged ring 11 formed with the concave bottom 12, the flange being held within the cylinder to form an impervious joint by rivets 13 or analogous means as preferred.

Circumjacent the upper edge of the tank is a heavy beading 15, re-enforcing its open upper end and below the bead are a plurality of forked lugs 16 rigidly attached to the wall of the tank in uniform spaced relation by rivets 17 or otherwise as may be preferred.

A pair of outstanding loop handles 18 are secured on opposite sides of the tank, above the center of its length, for convenience in carrying the same.

Pivoted between each pair of forks ex-

tending from the lugs 16, on removable pins 19, are the enlarged and flattened ends 20 of bolts 21, their screw-threaded portions 22 being provided with nuts 23, said bolts 60 being sufficiently long to extend over a cover plate (not shown) and secure the closure to the tank.

All of these several parts are hot-dipped galvanized to prevent rusting, discoloration 65 of paints and deterioration and the tank is straight sided and fully open at the top for filling and cleaning.

The interchangeable containers or cans 25 are made of lighter material, having bottoms 26 flanged to extend as a band 27 over the lower edge of the can and have a reinforcing band 28 at the top, over which may be engaged a cover 29 its downturned flange 30 loosely fitting over the re-enforced 75 edge.

A bail 31 made of a single thick strand of wire, is bent into a semi-circle, its ends 32 extended horizontally outward to pass through the wall of the can and then may 80 be upset, as at 33 to prevent inadvertent displacement.

Adjacent one of the bail ends 32, on each side thereof, are fixed studs or rivets 34 their function being to act as supports 85 for the bail when turned horizontally in either direction and prevent it from entering the paint immediately below.

This arrangement presents several advantages, one of which is the easy exchange 90 of the can for another having contents of different material, color, density, etc., the bail always being readily accessible and so arranged that the hands need not be soiled in exchanging the cans.

It is also to be noted that the interior of the tank is at all times free from the material to be dispensed and that the air space intervening between the can and tank acts to equalize the pressure in the manner of a 100 reservoir.

Although the foregoing is descriptive of the preferred embodiment of the invention, it will be apparent that minor changes may be made in its construction, without the exercise of invention or conflicting with the scope of the claims hereto appended.

Having thus described my invention, what I claim as new and desire to secure 110 by Letters Patent, is:—

1. In an apparatus for spraying paint under pressure, a cylindrical tank adapted to

- withstand internal pressure, said tank having a closed concave bottom and being open at the top, a plurality of cover securing means adjacent the upper edge of said tank, handles fixed on opposite sides of said tank, interchangeable paint containing means spaced concentrically within the tank, a band circumjacent the lower edge of said paint containing means adapted to rest upon the bottom of said tank, said band being flanged upward from the bottom element, a semi-circularly bent rod forming a bail for the container, pintles extending outwardly from the ends of said bail pivoted in the container wall, stops fixed in the wall extending into the container, said stops being adapted to support said bail when resting horizontally thereon, and a cover loosely fitting over said paint containing means below the plane of the upper edge of said tank.
- 10 2. In an apparatus for spraying paint under pressure, a cylindrical tank adapted to withstand internal pressure, said tank having a closed concave bottom and being open at the top, a plurality of outstanding forked lugs adjacent the upper edge of said tank,
- 15 bolts pivoted between the forks of said lugs, said bolts being provided with nuts to secure a cover, handles fixed on opposite sides of said tank, a paint container spaced concentrically within the tank, a band circumjacent the lower edge of said container adapted to rest upon the bottom of said tank, said band being flanged upward from the bottom element, a semi-circularly bent rod forming a bail for the container, pintles 30 extending outwardly from the ends of said bail pivoted in the container wall, stops fixed in the wall extending into the container, said stops being adapted to support said bail when resting horizontally thereon, and a cover loosely fitting over said container below the plane of the upper edge of said tank.
- 20 This specification signed and witnessed this 8th day of September, 1922.
- 25 WILLARD C. BEACH.
